UNITED STATES PATENT OFFICE.

EDWARD S. PEAKE, OF WESTERVILLE, OHIO.

TOY PISTOL.

Application filed February 21, 1924. Serial No. 694,357.

This invention relates to toy firearms of the type intended for the explosion of percussion caps.

The invention is an improvement upon the device disclosed in the patent to Adams, 859,032, granted July 2nd, 1907, and may be embodied in a pistol comprising an anvil, a hammer, preferably reciprocable and normally maintained in engagement with the anvil, a trigger for retracting the hammer from the anvil, and a feed pawl for intermittently moving a strip of caps over the anvil to present caps successively to the hammer.

An object of the invention is to render the operation of the pistol, so far as its mechanism is visible, very similar to the usual firearm, and to insure the feeding of the caps over the anvil, as the trigger is operated, without mutilating or buckling the strip.

A further object of the invention is to provide a firearm which may be readily operated by a comparatively light pressure applied directly to the trigger, and to effect the feeding of the caps over the anvil by this same pressure, which is directly applied to the feeding pawl.

The invention also aims to provide a simple and effective means for retracting the hammer, permitting the latter to have a simple rectilinear reciprocatory movement, thus reducing the likelihood of the parts becoming relatively displaced.

Additional objects of the invention, such as the simplification of the mechanism, the provision of a firearm which may be cheaply manufactured and sold, and the affording of a comparatively simple device, which may be readily cleaned and from which the particles of the exploded caps will be freely discharged, will become apparent as the description proceeds in connection with the accompanying drawings, illustrating a preferred embodiment thereof, and wherein:

Figure 1 is a side elevational view.

Figure 2 is a longitudinal sectional view with the parts in their normal positions.

Figure 3 is a view similar to Figure 2 showing the relative positions of the parts at an intermediate stage in the operation of the pistol, and just prior to the releasing of the hammer for the explosion of a cap.

Figure 4 is a view similar to Figure 3 showing the relative positions of the parts at the explosion of a cap.

Figure 5 is a cross sectional view on the

line 5—5 of Figure 3, looking in the direction of the arrows.

Figure 6 is a perspective of the hammer, and

Figure 7 is a perspective of the feeding pawl.

Referring to the drawings for a more detailed explanation of the invention, the mechanism is enclosed within a casing which is preferably formed in two sections 10, 11 held together as by a transversely extending bolt 11' upon the end of which is secured a nut 11''. The casing has a barrel portion 12 and a grip or stock 13, the interior of the latter being rendered accessible by a swinging closure 14 pivoted at 15 to the casing section 10. Upon the interior of the casing at the upper end of the grip, and preferably upon one of the casing sections, in the present instance the section 11, is formed a vertical wall 16 constituting an anvil, the top of the grip above the anvil as at 17 having a forwardly flaring hood 18 and an opening 18' directed toward the muzzle through which the particles of the exploded caps may be discharged forwardly and away from the operator.

Directly below the anvil, and preferably in the end of the stock or grip, is provided an opening 19, through which a strip of caps may be introduced into the pistol. It will be noted that the interior of the stock between the opening and the anvil is unobstructed so that the cap strip may be fed over the anvil without bending the strip, thereby offering a minimum of resistance to the feeding movement. Moreover, the opening 19 permits the particles of the exploded caps and the strip to drop by gravity from the pistol so that the burned particles do not accumulate within the revolver and interfere with the operation of the mechanism.

Positioned within the barrel and movable toward and from the anvil is a hammer 20 having a striking face 21, which is maintained against the anvil by means of a spring 22 surrounding the shank 23 of the hammer and abutting a collar 24 thereon. The other end of the spring abuts one of a pair of bearings 25, 26 for the hammer, the bearings being formed in halves upon the separate casing sections. These bearings serve to direct the hammer in a substantially straight or rectilinear path so that the movement toward and from the anvil is a simple rectilinear one, which is preferable.

The hammer is retracted from the anvil by means of a trigger 27, the lower end 28 of which is rearwardly and then forwardly curved to form a substantially half loop. The trigger is fulcrumed upon a stud 29 on the casing section 11, and has a forwardly and upwardly projecting end 30 above its fulcrum carrying a stud 31, serving as means for connecting to the trigger a drag link 32. 10 The link 32 is, preferably, pivotally mounted upon the stud 31, at one end, and its free end has formed thereon suitable means for engaging the hammer. A laterally projecting lug 33 upon the link serves this purpose, and its forward end 34 engages the face of a shoulder 35 upon the hammer. The shoulder is formed by means of a substantially V-shaped notch 36 cut in the hammer, and as will be noted, the shape of the lug 33 15 is such that the top surface of the same engages substantially flush with the approximately horizontal surface 37 of the notch 36. A spring 38 encircles the stud 31 and has one end 39 anchored upon the end of the trigger with its other end 40 engaging the drag link 32 at an intermediate point so as to urge the link upwardly to engage the hammer. The trigger is held in the position shown in Figure 1 by a substantially V-shaped spring 44 coiled at an intermediate 20 point about the stud 29 and having its free ends engaging the casing flange and the under surface of the trigger projection 30, respectively. The spring thus serves to move the trigger in a clockwise position about its pivot, this being limited by the engagement of the forward edge of the trigger, as indicated at 45, with the casing flange. As the trigger is actuated, the upper end 39 moves 25 downwardly and also forwardly somewhat, first, serving to retract the hammer from the anvil, as will be noted from an inspection of Figure 3. The spring 38 maintains the forward face of the lug 33 in engagement with a shoulder 35 and also the top surface of the lug in engagement with a corner 48 upon the lower edge of the hammer. The downward movement of the end of the trigger to which the drag link is connected being continued 30 from the position shown in Figure 3, serves to pivot the free end of the link about the corner 48 of the hammer and to disengage the shoulder 35 and the forward face of the lug, thereby permitting the spring 22 35 to throw the hammer against the anvil. Release of the trigger then permits the spring 41 to return the same to normal position shown in Figure 2.

It will be apparent that the drag link is 40 bodily moved forwardly within the casing by the trigger, and that at the same time the end of the link connected to the trigger is drawn downwardly or laterally with respect to the path of movement of the hammer. During this movement, the spring 38

maintains the top surface of the lug 33 in engagement with the corner 48 of the hammer so that as the downward or lateral movement of the end, which is connected to the trigger, progresses the corner 48 serves as a 70 center or axis of pivotal movement of the link until the lug and shoulder 35 are disengaged, thereby permitting the spring to throw the hammer against the cap upon the anvil. 75

The action of the trigger and link in retracting the hammer and in releasing the latter is very positive and allows a sudden release which permits the full force of the spring to be exerted in forcing the hammer against the anvil. Upon the return of the drag link and trigger to normal position (Fig. 2), the top surface of the lug 33, which is at all times in contact with the bottom surface 35' of the shoulder, moves across 80 this surface, and the free end of the link is thereby maintained depressed by the shoulder until the link reaches the position shown in Figure 2.

The invention contemplates the automatic 90 feeding of the strip of caps across the face of the anvil to present caps successively to the firing face 21. The caps may be employed in the form of a roll as shown in the patent to Adams, referred to, in which event 95 a suitable support within the stock would be provided. Preferably, however, the strip is fed into the stock in lengths of ten or twelve caps uniformly spaced apart, a strip of caps C being shown, for example, in Figure 2. A feeding pawl 50 has a finger piece 51 positioned beside and slightly forwardly of the trigger when the parts are in normal position (Fig. 2) and the pawl is connected to the trigger, as by means of a hook 52 105 upon the trigger projecting through a loop 53 upon the end of the pawl finger piece 51.

Referring to Figure 8, it will be noted that the pawl, at the connecting loop 53 in the present instance, overlaps the trigger so that 110 pressure upon the pawl is necessarily applied during the initial stages of the pawl movement to the trigger. The connection between the two is a loose one, permitting the pawl to move relative to the trigger to the 115 desired extent, as the latter is actuated, and when the parts reach the position shown in Figure 2, the pawl finger piece and trigger are both directly engaged so that the pressure is applied directly to the trigger, thereby rendering unnecessary increased pressure to the feeding pawl in order to actuate the trigger in opposition to the trigger spring, the resistance of which gradually increases. The end of the pawl 50' is pressed against the 120 strip of caps upon the anvil and continuation of the trigger movement carries the pawl upwardly in a path approximately paralleling the face of the anvil. By positioning the finger piece of the pawl beside the 125

trigger, it is not necessary to increase the pressure upon the pawl as the feeding movement progresses and as the resistance of the spring 44 increases. When the finger piece 5 of the pawl and the trigger are side by side, as shown in Figure 2, continued movement of the trigger is accomplished by direct pressure upon the trigger and not through the pawl.

10 As indicated in Figure 2, the pawl has moved the cap strip a sufficient distance to carry a cap into horizontal alignment with the face of the hammer, and the hammer is about to be released. It is desirable to prevent the continuation of the feeding movement after the hammer engages the cap, for the reason that any further movement of the strip would buckle and mutilate the same, since the strip is clamped between hammer 15 and the anvil. In order to prevent a feeding action by the pawl after the hammer has exploded the cap, means is provided for carrying the end of the pawl away from the face of the anvil and strip when the latter has 20 been moved the necessary distance over the face of the anvil. For this purpose a projecting lug 56 is positioned in the path of the pawl, and as the latter is moved upwardly, a recess 57 cut inwardly from one edge passes 25 over the projection. The projection being inclined at an angle to the face of the anvil serves to direct the pawl away from the latter, as indicated in Figure 4. Upon the return movement of the trigger and the actuation 30 of the return spring 44, the pressure upon the pawl having been relieved, the end of the same rests lightly upon the cap strip and does not tend to carry the strip downwardly, the strip being held in position by 35 the hammer engaging the portions of the same around the exploded cap.

When in the position shown in Figure 2 prior to operation, the pawl is supported by means of a lug 58 upon the interior of the 40 casing.

The feeding construction provided permits direct pressure both upon the trigger and the feeding pawl instead of actuation of the trigger through the medium of the pawl or vice versa. The provision of the spring for 45 returning the trigger to normal position instead of relying upon the operator avoids the danger of any pressure being placed upon the pawl as the latter descends, since any weight upon the pawl urging the same against the face of the anvil in the pawl return movement would quickly mutilate and 50 destroy the strip, or at least carry the same out of position.

60 I claim:

1. A toy firearm comprising an anvil, a hammer, a trigger for actuating the hammer, said trigger having a manually engageable portion for actuation thereof, and a feeding pawl loosely connected to the trigger and

having a portion adapted to be manually engaged, when the trigger is actuated, to press the pawl against the anvil, the said pawl operating automatically upon movement of the trigger to feed a strip of caps 70 over the anvil.

2. A toy firearm comprising an anvil, a reciprocable hammer, means for guiding said hammer, a trigger for actuating the hammer, said trigger having a portion directly engageable for actuation thereof, and a feeding pawl loosely connected to the trigger and having a portion adapted to be manually engaged, when the trigger is actuated, to press the pawl against the anvil, the said 75 pawl operating automatically upon movement of the trigger to feed a strip of caps over the anvil.

3. A toy firearm comprising an anvil, a reciprocable hammer, means for guiding 80 said hammer and preventing movement of the same laterally with respect to its path of reciprocation, a trigger for actuating the hammer, said trigger having a portion directly engageable for actuation thereof, and a feeding pawl loosely connected to the trigger and having a portion adapted to be manually engaged, when the trigger is actuated, to press the pawl against the anvil, the 85 said pawl operating automatically upon movement of the trigger to feed a strip of caps over the anvil.

4. A toy firearm comprising an anvil, a hammer, yielding means for normally maintaining the hammer in engagement with the anvil, a trigger for actuating the hammer, said trigger having a directly engageable fingerpiece and a manually engageable feeding pawl loosely connected to the trigger and movable relatively to the trigger into 100 engagement with the anvil by the pressure exerted during the operation of the trigger, said pawl serving to feed a strip of caps over the anvil.

5. A toy firearm comprising an anvil, a reciprocable hammer, means for guiding the hammer, yielding means for normally maintaining the hammer in engagement with the anvil, a trigger for actuating the hammer, said trigger having a directly engageable 110 finger piece and a manually engageable feeding pawl loosely connected to the trigger and movable relative to the trigger into engagement with the anvil by the pressure exerted during the operation of the trigger, said 115 pawl serving to feed a strip of caps over the anvil.

6. A toy firearm comprising an anvil, a rectilinearly reciprocable hammer, means for guiding said hammer and preventing movement of the same laterally with respect to its path of reciprocation, a trigger for actuating the hammer, and a feeding pawl loosely connected to the trigger and operating automatically upon movement of the 125 130

- trigger to feed a strip of caps over the anvil, said pawl having a finger piece directly engageable to press the pawl against the anvil when the trigger is actuated.
- 5 7. A toy firearm comprising an anvil, a hammer, tension means for normally maintaining the hammer against the anvil, a trigger for actuating the hammer, and a feeding pawl having a finger piece positioned slightly forwardly of the trigger and adjacent the latter whereby the pawl may be pressed against the anvil when the trigger is actuated.
- 15 8. A toy firearm comprising an anvil, a hammer, tension means for normally maintaining the hammer against the anvil, a trigger for actuating the hammer, and a feeding pawl having a finger piece positioned slightly forwardly of the trigger and adjacent the latter whereby the pawl may be pressed against the anvil when the trigger is actuated, said pawl being connected to the trigger and movable therewith to feed a strip of caps over the anvil.
- 25 9. A toy firearm comprising an anvil, a hammer, tension means for normally maintaining the hammer against the anvil, a trigger for actuating the hammer, and a feeding pawl having a finger piece positioned slightly forwardly of the trigger and adjacent the latter whereby the pawl may be pressed against the anvil when the trigger is actuated, said pawl finger piece being connected to the trigger and movable therewith to feed a strip of caps over the anvil.
- 40 10. A toy firearm comprising an anvil, a hammer, a manually engageable trigger for actuating the hammer, a feeding pawl having a finger piece positioned beside the trigger, said finger piece being manually engageable when the trigger is actuated to press the pawl against the anvil, and the pawl being movable with the trigger to feed a strip of caps over the anvil.
- 45 11. A toy firearm comprising an anvil, a hammer, a trigger for actuating the hammer, a feeding pawl having a finger piece positioned beside the trigger and slightly forwardly of the latter, said finger piece being manually engageable with the trigger when the latter is actuated to press against the anvil, and the pawl being movable with the trigger to feed a strip of caps over the anvil.
- 55 12. A toy firearm comprising an anvil, a hammer, a trigger for actuating the hammer, a feeding pawl having a finger piece positioned beside the trigger, said finger piece being manually engageable with the trigger when the latter is actuated to press the pawl against the anvil and the pawl being movable with the trigger to feed a strip of caps over the anvil, said pawl finger piece and the trigger being connected to insure movement of the pawl and trigger together.
13. A toy firearm comprising an anvil, a hammer, a trigger for actuating the hammer, a feeding pawl having a finger piece positioned beside the trigger and slightly forwardly of the latter, said finger piece being manually engageable with the trigger when the latter is actuated to press against the anvil and the pawl being movable with the trigger to feed a strip of caps over the anvil, said pawl finger piece and the trigger being connected to insure movement of the pawl and trigger together. 70
14. In a toy firearm, an anvil, a hammer, a trigger for actuating the hammer, a feeding pawl connected to the trigger and receiving the pressure exerted during the operation of the trigger to feed a strip of caps over the anvil and means for directing the pawl away from the anvil in its feeding movement at an intermediate point in its path of travel. 80
15. In a toy firearm, an anvil, a hammer, a trigger for actuating the hammer, a feeding pawl connected to the trigger and receiving the pressure exerted during the operating of the trigger to feed a strip of caps over the anvil and a guide lug positioned in the path of travel of the pawl serving to direct the pawl in its feeding movement away from the anvil after a cap has been engaged by said hammer. 90
16. In a toy firearm an anvil, a hammer, a trigger for actuating the hammer, a feeding pawl for a cap strip actuated by movement of the trigger, said pawl moving over the surface of the anvil, and means for moving the pawl away from the anvil in its feeding movement after a cap has been exploded by the hammer thereby preventing buckling of the cap strip as the pawl continues its feeding movement. 100
17. In a toy firearm an anvil, a hammer, a trigger for actuating the hammer, a feeding pawl for a cap strip actuated by movement of the trigger, said pawl moving over the surface of the anvil, and means positioned on the path of the pawl for moving the pawl in its feeding movement away from the anvil after a cap has been exploded by the hammer thereby preventing buckling of the cap strip as the pawl continues its feeding movement. 110
18. In a toy firearm, a casing having a barrel portion and a stock portion extending at an angle to the barrel portion, an anvil in said stock portion extending substantially longitudinally thereof, a hammer, means for actuating the hammer, said stock having an outlet and discharge opening substantially directly below the anvil to permit a strip of caps to be fed over the anvil from said opening in a rectilinear path and to permit gravitation of particles of exploded caps directly through the opening, the interior of the casing being unobstructed below the anvil and between the same and said opening. 120
- 125
- 130

19. In a toy firearm, a casing having a barrel portion and a stock portion, an anvil in said casing, a hammer, means for actuating the hammer, said casing, having an opening substantially directly below the anvil and the interior thereof being unobstructed below the anvil between the same and said opening whereby particles of exploded caps may gravitate through said opening.

20. In a toy firearm, an anvil, a rectilinearly reciprocable hammer, a trigger for

actuating said hammer, a drag link pivotally connected to said trigger and operatively associated with the hammer to retract the latter from the anvil when the trigger is moved, said trigger serving to rock the link about a pivotal point spaced from its point of connection with the trigger and thereby to disengage the same from the hammer.

In testimony whereof I have hereunto set my hand.

EDWARD S. PEAKE.
